22 Claims. (Cl. 66—86)

This invention relates to warp knitting machines. Such machines may be provided with needles arranged to co-operate with independent tongues and such a needle comprises a tubular or grooved shank having a hook at one end, the tongue being arranged to move to and fro relatively to the needle between a position in which the tip of the tongue covers the needle hook and a position in which the tip of the tongue is withdrawn into the groove or bore in the shank. The relative movement is usually effected by imparting to-and-fro movement both to the needle and to the tongue. These elements may be mounted to move in a vertical straight line path. In that event, the side of the needle on which the tip of the hook lies may be referred to as the front of the needle and this side is so referred to as the front of the needle and this side is so referred to below, although it is to be understood that the needles and tongues may be arranged to move in horizontal or oblique straight-line paths. They may also be moved in arcuate paths and then the needle shanks and tongues may be made arcuate in the planes of the hooks.

In these needles, there is a tapered part joining the main part of the shank to the hook and, during each knitting cycle, the tapered part is passed through a loop of yarn, previously drawn by the hook, to enable the associated tongue to pass through the loop from the position in which it is concealed in the shank groove or bore. When, however, the tongue is withdrawn from the hook, yarn is laid over the front of the tapered part. Then, as the tongue passes through the loop, the needle is withdrawn to draw the newly laid yarn into a loop which is pulled through the previous loop as the latter is cast off over the end of the hook, while the hook is closed by the tip of the tongue overlapping the hook.

Now the tension on the loop of yarn being cast off over the tongue may be considerable and the tip of the tongue is unsupported between the time when it begins to emerge from the groove or bore in the shank and the time when it overlaps the tip of the needle hook. Accordingly, if the tip of the tongue is thus unsupported when a loop is being cast off, the load due to the yarn may bend the tip of the tongue to an undesirable extent. The result may then be that damage is done by the tip of the tongue colliding with the tip of the needle hook or that a flaw arises in the fabric due to the loop, which ought to be cast off, becoming caught on the tip of the needle hook or moving back into the hook.

According to the present invention, therefore, a warp knitting machine is provided with mechanism for imparting to hook needles and to independent tongues, allocated respectively to the needles and arranged to cover the needle hooks when loops are cast off from the needles, to and fro motion such that the tongues undergo no substantial movement relatively to the needles, while covering the needle hooks, throughout a substantial part of each of those strokes of the needles, that result in the casting off of the loops. Thus, the tongues are arranged to overlap the needles quite near the beginning of the needle strokes in which new loops are drawn, and remain overlapping, throughout the major parts of these strokes, until the previously drawn loops are cast off. The tongues are, therefore, in position to be supported by the needle hooks so long as the tongues are in contact with loops being cast off. The absence of substantial relative movement during this process, means that movement accompanied by substantial friction, due to the load of the yarn on the tongues, is avoided.

In a warp knitting machine, the threads are laid or lapped on the needles by warp guides, and a warp guide in any one cycle of operation may be caused to pass between a pair of needles to the back thereof. Very often, two or more warp guides are arranged to pass between each pair of needles from the back to the front, and then the two warp guides are moved longitudinally in opposite directions to lap their respective threads over different needles, or in the same direction.

In a straight warp knitting machine, as distinguished from a circular warp knitting machine, the two or more warp guides arranged to pass between a given pair of needles are conveniently carried respectively by bars. Thus, each bar carries a row of warp guides, and to effect the lapping, it is convenient to swing each bar about a longitudinal axis to bring the associated warp guides from the back to the front of the needles. Each bar is then moved longitudinally so that the warp guides pass across the fronts of the needles. Next, the bars are swung to bring the warp guides from the front to the back of the needles. The two or more warp guides passing between a pair of needles, follow one another as they pass the needles.

When two or more warp guides pass between a pair of needles, it has been found highly desirable for the warp guide eyes to traverse substantially the same path relatively to the needles. This enables the yarn to be accurately laid on the needles. Furthermore, in warp knitting ma-

chines designed to run at very high speeds it is essential to keep the inertia forces low while retaining sufficient strength in the moving parts to resist deflection. Thus, those parts that might otherwise give rise to undesirable high inertia forces or moments must be given as much time as possible for their movements. The timing of the parts, therefore, is of extreme importance for it determines both the manner in which the knitting parts co-act and the nature of the inertia loads.

Accordingly the invention involves a warp knitting machine provided with mechanism for imparting to hook needles to-and-fro movement and with tongues allocated respectively to the needles and arranged to cover the needle hooks when loops are cast off from the needles, in which the said to-and-fro movement includes a phase which is actually or substantially a dwell extending over the period starting when the warp guides are passing between the needles before lapping and ending when the warp guides are passing between the needles after lapping. The dwell occurs when the needles are at the top of their stroke prior to drawing a new loop. The needles need not be quite stationary during the dwell but may undergo slight movement. The whole of the needle movement is arranged to take place so that the accelerations are as small as possible consistent with the correct motions for knitting, and may be such that the movement consists of harmonic components which are not of high frequency in relation to the machine speed or include high frequency components of as small amplitude as possible. It has also been found advantageous to arrange the driving mechanism for the tongues so that these remain substantially stationary, or move quite slowly, while the warp guides lay the threads safely in the needle hooks without contact with the tips of the tongues.

It has also been found practical for the tongue movement to include a dwell, in this fashion, when the needles are arranged to move to-and-fro with simple harmonic motion and without any marked dwell. Then, however, the needle stroke must be greater than in the case where provision is made for the needles to dwell. In regard to this aspect of the invention, the main consideration is that the tips of the tongues shall remain concealed in the needle shanks for a period starting when the newly formed loops are passing up the last portions of the tapered parts of the needles and ending when the warp guides are passing between the needles after lapping. The reason for this is that there are limits to the proportion of each knitting cycle that can be occupied by the lapping movement of the warp guides and in order to insure clear paths for the threads as they are laid on the needles, the tips of the tongues should not just momentarily be withdrawn into the needles shanks. The movements of the tongues may consist of harmonic components, with accelerations as small as possible, which combine to give the necessary dwell.

The required movements can be imparted to the needles and tongues through the medium of cams. However, it has been found possible to drive the needles or the tongues, when the movements of these elements are to include phases which are actually or substantially dwells, by means of eccentrics. In that event, two or more eccentrics acting in parallel and running at different speeds are used to drive the needles, and

a similar arrangement is used for the tongues. These eccentric arrangements have certain advantages over cams in high speed knitting machines. The high inertia forces of the assemblies impose such high loads upon the cams that they must be constructed of high grade materials and submitted to intricate and special heat treatment to withstand the heavy loads put upon them. Very great care must be taken that the oil film between cam and cam follower remains intact and force feed lubrication has to be provided to ensure an adequate supply of oil. The accuracy required in the cams is such as to make the use of a cam and countercam arrangement inexpedient, and without such an arrangement the followers must be held on the cams by springs.

When eccentrics are substituted for these cams, they can be manufactured from ordinary mild steel, because the inertia forces at high speed can be distributed over the greater surface areas through the eccentric straps. "Splash" lubrication may be used, and accurate production is neither difficult nor expensive.

A particular feature of the invention, consists in arranging the sinkers in a warp knitting machine to be operated by eccentrics acting in parallel and running at different speeds. It has been found that the somewhat elaborate motion required for the sinkers can be imparted simply and effectively by such an eccentric arrangement.

In order that the invention may be clearly understood and readily carried into effect, some constructions in accordance therewith will now be described, by way of example, with reference to the accompanying drawings, in which:

Figure 1 is a vertical section through part of a warp knitting machine;

Figure 2 is a timing diagram showing the movements of the knitting elements in the machine;

Figure 3 is a sectional elevation of parts for driving the knitting needles in the machine;

Figure 4 is a sectional elevation of parts for driving the warp guides in the machine;

Figure 5 is a sectional elevation of sinker mechanism in the machine;

Figure 6 is a sectional elevation on the line VI-VI in Figure 12 of part of another warp knitting machine;

Figure 6A shows further details of the machine appearing in Figure 6.

Figure 7 is a sectional elevation of part of a third form of warp knitting machine;

Figures 8, 9, 10 and 11 show modifications of certain parts appearing in Figure 6;

Figure 12 is a sectional front elevation of the right hand half of the machine appearing in Figure 6.

The machine to be described with reference to Figures 1 to 5 has a row of knitting needles 1, Figure 1, which are carried vertically and side by side by blocks 2. The latter are mounted side by side on a long needle bar 3 to which they are secured by clamp plates 4. The needle bar 3 is supported at points distributed along its length by members 5 at the upper ends of vertical rods 6 which respectively extend upwards from casings 7, one of which is shown in Figure 3. Each rod 6 is mounted for to-and-fro vertical movement in guides 8 in its associated casing 7 and the vertical movement is imparted by eccentrics 9 and 10 carried by shafts 11 and 12. The shafts 11 and 12 are the main driving shafts of the machine and, during the operation of the machine, they rotate uniformly but the shaft 12 is driven at twice the speed of the shaft 11. These eccen-

trics are embraced respectively by straps 13 and 14 on eccentric rods 15 and 16. The latter are pivoted respectively at 17 and 18 to the ends of a two-armed lever 19 pivoted at its centre at 20 to the rod 6. The two-armed lever 19 consists of two parts lying respectively in front of and behind the eccentric rods 15 and 16 and the rod 6.

The throws of the eccentrics and their phase relationship is such that the needles 1 move up and down in the manner shown by curve A in Figure 2. It will be seen that the needles rise smoothly to their uppermost positions and that there is then a period in which the needles are substantially stationary. The needles then descend smoothly. The period of dwell extends approximately between the instants occurring at 100° and 220° in each knitting cycle of the machine. However, the needles move during this period of dwell upwards 0.02 inch and then move down 0.02 inch. The machine being described is a 28 gauge machine (i. e. there are 28 needles per inch length of the needle bar).

Each needle 1 has a tubular shank which is tapered at its upper end 1a and merges into the needle hook 1b. The needles extend through the blocks 2 and a tongue 21 extends upwards into the shank of each needle. The tongues 21 are carried by blocks 22 secured to a long tongue bar 23 by clamp plates 24. When it is desired to remove any one of the needle blocks 2 a nut 4a on bolt 4b passing through a clamp plate 4 and through the needle bar 3 is released to permit a spring 4c to urge the clamp plate upwards. If the clamp plate 24 is also released, the needle block 2 with the associated tongue block 22 can be removed from the machine for repair or replacement. It will be seen that the clamp plate 4 is remotely operated by the actuation of the nut 4a. This is because the clamp plate 4 is in a somewhat inaccessible position.

The tongue bar 23 is mounted at the top of rods 25. There are as many of these rods 25 as there are rods 6 supporting the needle bar 3, and the rods 25 pass respectively into the casings 7. As viewed in Figures 1 and 3, each rod 25 lies behind the associated rod 6. The rods 25 are constrained to move up and down in a vertical direction in the same way as the rods 6, and are driven by eccentrics on the shafts 11 and 12. The mechanism connecting the eccentrics for driving the tongues 21 to the rods 25 is similar to the mechanism connecting the rods 6 to the eccentrics 9 and 10. The throws of the eccentrics associated with the tongues and their phase relationship is such that the tongues move up and down in the manner shown by curve B in Figure 2. It will be seen that the tongues remain substantially stationary during the first 60° of the period of needle dwell and then during the remaining 60° of that period travel upwards a distance of about 0.14 inch.

It is during the period when the needles are substantially stationary that threads are positioned in the needle hooks by the warp guides 26 (Figure 1). There are two rows of these warp guides, the rows being carried respectively by guide bars 27. These guide bars are carried by a shaft 28 which is rocked to and fro about its axis. Furthermore, the guide bars, as is usual, can be moved longitudinally to and fro relatively to the rock shaft 28. In each cycle of operation of the machine the warp guides 26 are first swung so as to pass between the needles from the backs to the fronts thereof. Figure 1

shows the warp guides in the course of such movement. The leading warp guides pass between the needles substantially at the point a in curve C of Figure 2 which represents the 5 swinging motion of the warp guides in each cycle of operation. As soon as the warp guides have passed between the needles they are moved longitudinally so as to position the thread upon the fronts of the needles. The longitudinal movement of the warp guides is represented by a curve D in Figure 2, and the warp guides pass across the fronts of the needles between the instants c and d. After this lapping has taken 10 place the warp guides are swung back from the fronts of the backs of the needles, the leading warp guides passing between the needles in the vicinity of the instant b in Figure 2. The fact that the needles are substantially stationary during this swinging operation of the warp 15 guides enables the threads to be laid in precisely the required positions relatively to the length 20 of the needles.

The timing of the needles and tongues, in addition to enabling the warp guides to pass between the needles in the desired paths relatively to the needles, has further advantages in that it gives considerable latitude in the timing of the other knitting parts. For example, the 25 oscillation of the warp guides about the axis of the shaft 28 takes place over a period of about 220° (between the instants e and f, Figure 2). If the needles did not dwell, this period would have to be shortened considerably or the needle 30 stroke increased substantially. The fact that 35 the oscillation of the warp guides can take place over a period of about 220° means that the inertia loads due to operating the warp guides, when the machine is running at very high speeds, do not rise objectionably. It also means that the 40 warp guides can be oscillated by multi-eccentric mechanism and the advantages inherent in such mechanism can be obtained.

It will be appreciated that the period of a complete oscillation of the warp guides, i. e. the 45 period between the points e and f (curve C) is substantially longer than the period during which the needles dwell, because the needles only have to dwell between the time when the warp guides are passing between the needles at the beginning of lapping and the time when the warp guides are passing between the needles at the end of lapping, and the warp guides move some distance in their oscillation about the axis 50 of the shaft 28 before reaching the backs of the needles and after passing between the needles in their return movement.

In the example being considered, the warp 55 guides are oscillated through the medium of units each driven by the pair of parallel horizontal shafts 11 and 12 (Figure 4). These shafts respectively carry eccentrics 32 and 33. The eccentrics are respectively embraced by straps 34 and 35 on eccentric rods 36 and 37. The upper ends of these eccentric rods are respectively pivoted to the ends of a two-armed lever 38 pivoted 60 at its mid-point at 39 to a rocker 40 pivoted about a fixed axis 41. The rocker 40 is connected to the rock shaft 28 through the medium of a link 45 pivoted at its upper end to an arm 42 (Figure 1) rigid with the rock shaft 28. The 65 eccentrics and mechanism immediately associated therewith are housed in a casing 43 and the link 45 passes with substantial clearance through an opening in the top of the casing. To prevent dirt entering the casing a bellows connection 44

is provided between the link 41 and the opening.

Because the eccentric 33 rotates at twice the speed of the eccentric 32 and because of the phase relationship between and the throws of the eccentrics, the warp guides are oscillated in the manner shown by the aforementioned curve C in Figure 2, and it will be seen that, when the warp guides have undergone the oscillation necessary for positioning the threads in the needle hooks, the warp guides are inevitably moved back slightly towards the backs of the needles, the extremity of this backward movement being at the point *g* in curve C.

Yet another advantage inherent in the timing of the needles and tongues is that the longitudinal movements of the warp guides across the fronts of the needles takes place in a period of 52° (i. e. the period between the points *c* and *d*), which is sufficient for the inertia loads, on the mechanism for moving the guide bars longitudinally, to remain within reasonable limits when the machine is operated at high speed. The guide bars are moved longitudinally by pattern wheels acting against return springs. The return longitudinal movements of the guide bars takes place between the points *h* and *i*, curve D.

After the threads have been positioned in the needle hooks the latter are moved downwards so as to draw loops in the threads and, during this downward movement, the tips of the tongues overlap the tips of the needle hooks. Then the tongues move downwards substantially at the same speed as the needles, with the tongues still overlapping the needle hooks. This overlapping takes place, as shown by the relationship of the curves A and B in Figure 2, between the instants *m* and *n*. It is between these instants that the loops drawn in the previous cycle of operation of the machine are cast off over the tips of the tongues and the ends of the needles. In this connection it will, of course, be understood that when the needles move upwards the loops drawn in the previous cycle pass over the tapered parts of the needle shanks so that the tongues can be projected through the loops.

It will have been appreciated from Figure 2 that the line A represents the movement of the tip of each needle hook while the curve B represents the movement of the tip of the associated tongue. It will be seen that during the period that the threads are being laid on the needles, that is the period intervening between the instants *a* and *b*, the tongue is concealed within the shank of the associated needle, and during the major part of the downward stroke of the needle the tip of the tongue is overlapping the tip of the needle so that the tip of the needle hook supports the tongue while the loop is being cast off.

It is during the casting off operation that the sinkers are operative and the timing of the needles and tongues, as shown by the curves A and B, provides considerable latitude for the timing of the sinkers enabling these also to be driven by multi-eccentric mechanism. Such mechanism is shown in Figure 5 and includes the shafts 11 and 12 respectively carrying eccentrics 52 and 53. These eccentrics are embraced respectively by eccentric straps 54 and 55 on eccentric rods 56 and 57. The upper ends of these eccentric rods are pivoted respectively at the ends of a two-armed lever 58 pivoted at 59 to a rocker 60 pivoted about a fixed axis 61. A link 62 connects the rocker 60 with an arm 63 fixed

to a rock shaft 64. The rock shaft 64 has arms 65 rigidly secured to it. Each arm 65 forms part of a Watt's parallel motion linkage including a member 67 pivoted at 66 to the arm 65 and at 68 to the upper end of a link 69 pivoted at its lower end about a fixed axis 70. These linkages give straight line movement to sinkers 71 projecting parallel to each other from blocks 72 secured to a sinker bar 73 mounted at the ends of the members 67. The location of the sinkers 71 relatively to the needles 1 is indicated by chain lines in Figure 5. The eccentric 53 is rotated at twice the speed of the eccentric 52, the shafts 11 and 12 being the main shafts of the machine. The sinkers move as shown by the curve E in Figure 2.

Eccentric driving units for the sinkers (like the one shown in Figure 5 which comprises a casing 74) may be distributed along the length of the rock shaft 64 or one such unit may be mounted towards each end of the rock shaft. Similarly, a unit such as that shown in Figure 4 may be mounted at each end of the rock shaft 28 for the guide bars. The arrangement of the eccentrics to provide the motions shown in Fig. 2, the angular setting given for each eccentric being the angle between the upward vertical line through the centre of its shaft and the eccentric throw measured in the direction of rotation of the shaft at the instant represented by 0° in Figure 2 is as follows:

	Shaft	Eccentric	Eccentric throw	Angular setting of eccentric
Needle.....	11	9	.406	193 30
	12	10	.131	192 45
Tongue.....	11	.....	.22	160
	12	.....	.134	193 30
Guide.....	11	32	.398	200
	12	33	.260	40
Sinker.....	11	52	.376	50
	12	53	.139	100

The knitting elements in the machine shown in Figure 6 are timed to operate substantially in accordance with Figure 2, but the disposition of the driving mechanism for the knitting elements is somewhat different from that in the machine described above. In Figures 3, 4 and 5 the mechanisms for driving the needles, warp guides and sinkers are shown separately but in Figure 6 these mechanisms are shown together so that their relative positions can be seen.

In the construction of Figures 6 and 12 there are parallel main driving shafts 80 and 81 connected by gearing 82 (Figure 6) such that the shaft 81 rotates at twice the speed of the shaft 80. These shafts respectively carry pairs of eccentrics such as 83 and 84 which impart to-and-fro motion to pairs of eccentric rods such as 85 and 86. The upper ends of such eccentric rods are pivoted respectively at the ends of a two-armed such as lever 87 pivoted at its centre 88 to a rocker 89 mounted to swing about a fixed axis 90. A link 91 connects this rocker 89 to an arm 92 fixed to a rock shaft 93. The latter has an upwardly extending arm 94 pivoted at 95 to a member 96 extending from the sinker bar 97. The member 96 is also pivoted at 98 to a link 99, pivoted to the machine frame at 100. There are, of course, a number of arms 94 distributed along the length of the rock shaft 93 (to support the sinker bar 97 along its length) and another such arm 94a appears in Figure 12. This is similarly connected to the driving shafts 80 and 81 through the medium of an arm 92a, a link 91a, a rocker

89a, pivoted at 88d to a two-armed lever 87d, which is connected by a pair of connecting rods such as 85a to eccentrics 83d and 84d on the shafts 80 and 81. Along the length of the needle bar 101 are distributed rods such as 102, which support the needle bar and which are constrained to move vertically by guides such as 103. At its lower end each rod 102 carries a two-armed lever 87d, similar to the lever 87, pivoted at its ends to eccentric rods such as 85a, similar to the eccentric rods 85, 86, driven by a pair of eccentrics 83a and 84a respectively on the shafts 80 and 81. Similar driving mechanism is provided for the tongues (see Figures 6A and 12), carried by the tongue bar 104, carried by rods such as 102a, similar to the rods 102. Each such rod 102a is pivoted at 88b to the centre of a two-armed lever 87b, similar to the lever 87. This lever is pivoted by connecting rods, such as 85b and 86b (Figure 6A), to a pair of eccentrics 83b and 84b respectively on the shafts 80 and 81. The warp guides 105 are swung about the axis of a rock shaft 106 by further pairs of eccentrics such as 83c and 84c (Figure 12) respectively on the shafts 80 and 81. These eccentrics are connected by eccentric rods such as 85c respectively to the opposite ends of a two-armed lever 87c, pivoted at its centre at 88c to a rocker 107, mounted to swing about a fixed axis 108 (Figure 6). A link 109 connects the rocker 107 to an arm 108a fixed to the rock shaft 106. It will be seen in Figure 6 that the tongue bar 104 lies in front of the needle bar 101, and that the latter lies in front of the sinker bar 97. Accordingly, in Figure 12 the tongue bar is shown broken away to uncover the needle bar 101, and the latter is also broken away to uncover the sinker bar 97.

Figure 7 shows a modified method of imparting the necessary to-and-fro motion to hook needles of the kind employed in the construction of Figure 6. In Figure 7 the motion of the needles is derived from eccentrics 110 and 110a respectively mounted on shafts 111 and 112, the shaft 112 being arranged to rotate at twice the speed of the shaft 111. The eccentrics 110 and 110a impart to-and-fro motion respectively to eccentric rods 113 and 114 pivoted at their upper ends to the ends of a two-armed lever 115. The latter is pivoted at its centre both to a rocker 116 and to a link 117. The rocker 116 is mounted to swing about a fixed axis 118 and the upper end of the link 117 is pivoted to one end of a two-armed lever 119 mounted to swing about a fixed axis 120. The end of the lever 119 remote from the link 117 is pivoted at 121 to a member 122 extending downwards from the needle bar 123. The lower end of the member 122 is pivoted at 124 to a link 125 which in turn is pivoted at 126 about a fixed axis. Owing to the fact that the perpendicular distance between the axes 120 and 121 is shorter than the perpendicular distance between the axes 124 and 126, the linkage including the member 122, the two-armed lever 119 and the link 125, provides a Watts parallel motion linkage, so that the needles 127 move in a path which is substantially a straight line. Actually the linkage is designed so that a straight line movement is imparted to the lower ends of the needles at which the tongues 128 enter the needles. There are, of course, a number of members similar to the member 122 distributed along the length of the needle bar 123, and each of these is associated with members similar to the lever 119, and with links similar to the link 125. The associated tongues are carried by a bar which is moved up

and down by mechanism similar to the mechanism shown in respect of the needles.

Figure 8 shows an alternative mechanism for driving the sinkers. In this the sinker bar 129 carries members 130, each pivoted at 131 to a link 132, which in turn is pivoted to the machine frame at 133. The member 130 is pivoted also at 134 to an arm 135 fixed to a rock shaft 136, the latter also carries an arm 137 connected by a link 138 to a rocker 139 pivoted about a fixed axis 140. A two-armed lever 141 is pivoted at 142 to the rocker 139 and the ends of the lever 141 are pivoted respectively to the upper ends of eccentric rods 143 and 144. Straps at the lower ends of these eccentric rods embrace eccentrics 145 and 146 carried respectively by shafts 147 and 148. The shaft 148 rotates at twice the speed of the shaft 147.

It is not essential that the sinker bar should be carried by a parallel motion linkage or a parallelogram linkage, but the sinkers may be arranged to rock about an axis. Thus, in each of Figures 9, 10 and 11, the sinker bar 149 is carried by arms 150 secured to a rock shaft 151. This rock shaft carries an arm (not shown) such as the arm 137 in Figure 8 or the arm 92 in Figure 6. This arm is connected to driving mechanism such as that shown in Figure 8 or in Figure 6.

We claim:

1. In a warp knitting machine, in combination, a plurality of hook needles mounted for to-and-fro movement, a plurality of tongues allocated respectively to said needles and mounted for to-and-fro movement relatively to said needles to cover and uncover the hooks thereof, a plurality of warp guides operative to lap threads on said needles, mechanism adapted to impart to said needles to-and-fro motion including a phase which is substantially a dwell and mechanism adapted to impart to said tongues to-and-fro motion including a phase which is substantially a dwell, said dwells occurring while said warp guides lay threads on said needles.

2. In a warp knitting machine, in combination, a plurality of hook needles mounted for to-and-fro movement, a plurality of tongues allocated respectively to said needles and mounted for to-and-fro movement relatively to said needles to cover and uncover the hooks thereof, a plurality of warp guides operative to lap threads on said needles, and mechanism, including a plurality of eccentrics acting in parallel and arranged to rotate at different speeds, connected to impart to said needles to-and-fro movement including a phase which is substantially a dwell extending over a period starting when said warp guides are passing between said needles at the beginning of lapping and ending when said warp guides are passing between said needles at the end of lapping.

3. The invention of claim 2 in combination with mechanism, including a plurality of eccentrics acting in parallel and arranged to rotate at different speeds, connected to impart to said tongues to-and-fro motion including a substantial dwell within said period of needle dwell.

4. In a warp knitting machine, in combination, a plurality of hook needles mounted for to-and-fro motion, a plurality of tongues allocated respectively to said needles and mounted for to-and-fro movement relatively to said needles to cover and uncover the hooks thereof, a plurality of warp guides operative to lap threads on said needles, and mechanism, including two eccentrics acting in parallel, connected to said needles and operative to impart thereto, when one

of said eccentrics is rotated at twice the speed of the other, to-and-fro motion including a phase which is substantially a dwell extending over a period starting when said warp guides are passing between said needles at the beginning of lapping and ending when said warp guides are passing between said needles at the end of lapping.

5. In a warp knitting machine, in combination, two eccentrics respectively mounted for rotation about parallel axes, two eccentric rods allocated respectively to said eccentrics and each including an eccentric strap embracing its respective eccentric, a lever pivoted at one point to one of said eccentric rods and at another point to another of said eccentric rods, and a needle rod mounted for straight line reciprocation, hook needles supported by said needle rod, the latter being pivoted to said lever to receive therefrom, when one of said eccentrics is rotated at twice the speed of the other, to-and-fro motion including a phase which is a substantial dwell.

6. In a warp knitting machine, in combination, a plurality of hook needles mounted for to-and-fro movement, a plurality of tongues allocated respectively to said needles and mounted for to-and-fro movement relatively to said needles, a plurality of warp guides mounted to swing to and fro about an axis, a rocker mounted to swing about a second axis and connected to said warp guides, two eccentrics, eccentric rods allocated respectively to said eccentrics and each including an eccentric strap embracing its respective eccentric, a lever pivoted respectively at two points to said eccentric rods and at an intermediate point to said rocker, whereby said warp guides are swung first from the backs of said needles to the fronts thereof and secondly from the fronts thereof to the backs thereof, and mechanism adapted to impart to said needles to-and-fro movement including a phase which is substantially a dwell extending between said first and second swinging movements.

7. In a warp knitting machine, in combination, a plurality of hook needles mounted for to-and-fro movement, a plurality of tongues allocated respectively to said needles and mounted for to-and-fro movement relatively to said needles to cover and uncover the hooks thereof, a plurality of warp guides mounted to swing about an axis and operative to lap threads on said needles, mechanism including two eccentrics acting in parallel and operative, when one eccentric is rotating at twice the speed of the other, to impart the swinging movements to said warp guides in the thread lapping operation, and mechanism adapted to impart to said needles to-and-fro movement including a phase which is substantially a dwell extending over the thread lapping operation.

8. In a warp knitting machine, in combination, a plurality of sinkers mounted for to-and-fro movement, and two eccentrics mounted to act in parallel and operatively connected to said sinkers to impart to same, when one said eccentric is rotating at twice the speed of other said eccentric, smooth to-and-fro movements alternating with relatively prolonged periods of dwell.

9. In a warp knitting machine, in combination, a plurality of sinkers, mounted for to-and-fro movement, two eccentrics respectively mounted for rotation about parallel axes, eccentric rods allocated respectively to said eccentrics and each including a strap embracing its respective eccentric, a lever pivoted at one point to one of said eccentric rods and at another

point to another of said eccentric rods, and a rocker pivoted to said lever at a point between said two aforementioned points and operatively connected to said sinkers.

10. In a warp knitting machine, in combination, a plurality of hook needles mounted for to-and-fro movement, a plurality of tongues allocated respectively to said needles to cover and uncover the hooks thereof, a plurality of warp guides operative to lap threads on said needles, and mechanism adapted to impart to said needles smooth to-and-fro movements alternating with substantial phases which are substantially dwells, a plurality of sinkers mounted for to-and-fro movement, and two eccentrics mounted to act in parallel and operatively connected to said sinkers to impart to same, when one said eccentric is rotating at twice the speed of other said eccentric, smooth to-and-fro movements alternating with relatively prolonged periods of dwell.

11. In a warp knitting machine, in combination, a plurality of hook needles mounted for to-and-fro movement, a plurality of tongues mounted for to-and-fro movement and allocated respectively to said needles to cover and uncover the hooks thereof, a plurality of warp guides operative to lap threads on said needles and mounted to swing to and fro about an axis in performing said lapping operation, a plurality of sinkers mounted for to-and-fro movement, and four mechanisms allocated respectively to said needles, tongues, warp guides and sinkers to impart said to-and-fro movements thereto, each said mechanism comprising a plurality of eccentrics mounted to act in parallel and operative when rotating at different speeds.

12. In a warp knitting machine, in combination, a plurality of hook needles mounted for to-and-fro movement, a plurality of tongues mounted for to-and-fro movement and allocated respectively to said needles to cover and uncover the hooks thereof, a plurality of warp guides operative to lap threads on said needles and mounted to swing to and fro about an axis in performing said lapping operation, a plurality of sinkers mounted for to-and-fro movement, and four mechanisms allocated respectively to said needles, tongues, warp guides and sinkers to impart said to-and-fro movements thereto, each said mechanism comprising two eccentrics mounted to rotate about parallel axes and operative when one of said eccentrics is rotating at twice the speed of the other.

13. In a warp knitting machine, in combination, a plurality of needle blocks, a plurality of substantially vertical hook needles secured parallel to each other in each block, a needle bar mounted for to-and-fro movement in a substantially vertical direction, a detachable clamp plate operative to secure said blocks to the top of said needle bar, a member adapted to secure said clamp plate upon said needle blocks and arranged to pass through said needle bar to a point where said member is readily accessible, a plurality of tongue blocks, a plurality of tongues secured parallel to each other in each tongue block and allocated respectively to said needles, a tongue bar mounted for to-and-fro movement, and a second detachable clamp plate operative to secure said tongue blocks to said tongue bar.

14. In a warp knitting machine, in combination, a plurality of needle blocks, a plurality of substantially vertical hook needles secured parallel to each other in each block and each said needle having a tubular shank, a plurality of

tongues respectively arranged to slide to and fro in said tubular shanks, a plurality of tongue blocks each carrying some of said tongues, a needle bar, a detachable clamp plate operative to hold said needle blocks on top of said needle bar, a member adapted to secure said clamp plate upon said needle blocks and arranged to pass substantially vertically through said needle bar to a point where it is readily accessible and a second detachable clamp plate operative to hold said tongue blocks on said tongue bar.

15. In a warp knitting machine in combination, a plurality of hook needles having tubular shanks, a plurality of tongues allocated respectively to the needles and operative to slide to and fro in said shanks, a plurality of warp guides mounted to swing to and fro between the needles and operative to lap threads on same, means for moving said tongues to and fro and means for moving said needles to and fro, said two means being adapted to cause the tips of said tongues to overlap the needle hooks and then to withdraw into said tubular shanks for a period starting when said guides are passing between said needles before lapping and ending when said warp guides are passing between said needles after lapping.

16. In a warp knitting machine in combination a plurality of hook needles having hollow shanks, a bar carrying said needles, a plurality of tongues allocated respectively to said needles and mounted to slide to and fro in said hollow shanks, a bar carrying said tongues, mechanism including two eccentrics arranged to turn uniformly at different speeds for imparting to-and-fro motion to said needle bar and mechanism comprising two eccentrics arranged to turn uniformly at different speeds for imparting to-and-fro motion to said tongue bar.

17. In a warp knitting machine in combination a plurality of hook needles having hollow shanks, a plurality of independent tongues allocated respectively to said needles and mounted to undergo movement relatively to same and mechanism for imparting to-and-fro motion to said needle bar including two eccentrics mounted to rotate uniformly at different speeds, eccentric rods adapted to be moved to-and-fro respectively by said eccentrics, a link interconnecting said eccentric rods, said link being pivoted at a point intermediate to said rods to a vertical pillar carrying at its upper end said needle bar.

18. In a warp knitting machine, in combination, a plurality of hook needles, a bar carrying said needles, an arm fixed to said bar, a lever pivoted at one point to swing about a fixed axis and, at a second point to said arm, a link pivoted

at a third point to said arm and at a fourth point to swing about a second fixed axis, the distance between said first and second points being greater than the distance between said third and fourth points, a rocker, a link connecting said rocker and said lever, two eccentrics connected to rotate at different speeds and eccentric rods respectively arranged to be moved to and fro by said eccentrics, said eccentric rods being operatively connected to said rocker to move same and said hook needles to and fro.

19. In a warp knitting machine in combination a plurality of sinkers mounted for to-and-fro movement, two eccentrics mounted to act in parallel and connected to rotate at different speeds, two eccentric rods respectively arranged to be moved to and fro by said eccentrics and mechanism interconnecting said eccentric rods and said sinkers to impart to same to-and-fro movement derived from said eccentrics.

20. In a warp knitting machine in combination sinkers mounted to rock to and fro about an axis, two eccentrics mounted to act in parallel, means connecting said eccentrics so that the latter rotate at different speeds, eccentric rods arranged to be moved to and fro respectively by said eccentrics and mechanism interconnecting said eccentric rods and said sinkers to impart to same swinging movement about said axis derived from said eccentrics.

21. In a warp knitting machine in combination a plurality of sinkers, substantially parallel pivoted arms supporting said sinkers, two eccentrics connected to rotate at different speeds, eccentric rods arranged to be moved to and fro respectively by said eccentrics and mechanism interconnecting said eccentric rods and one of said arms to move that arm to and fro about its pivotal axis.

22. In a warp knitting machine in combination a plurality of hook needles mounted to move forwards while threads are lapped on same and backwards while loops are cast away from said needles, a plurality of tongues allocated respectively to said needles and mounted for to-and-fro movement relatively to said needles to cover and uncover the hooks thereof and mechanism operative to impart to-and-fro motion to said needles and to said tongues such that said tongues undergo substantially the same movement as said needles while said tongues cover said needle hooks throughout a substantial part of each of the said backward movements of the needles that result in the casting off of loops.
